UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

COMBINED CAN FEEDER, DRAINER, AND SIRUPER.

Application filed July 18, 1927. Serial No. 206,492.

My invention relates to the canning art. In this art there is a stage which comprises supplying the cans with the relatively solid washed product; draining from them the 5 surplus moisture; and filling them with sirup. The machines employed in carrying out this period of operation are a can-feeder, a can-drainer supplied by the feeder, and which inverts and reverts the cans, and a 10 siruper to which the drained cans are carried by the feeder. These devices are virtually more or less separate machines, their assemblage in the line being usually due to a travelling belt conveyer, which, traversing 15 the plane of rotation of the drainer, yields its cans successively to its rotating propeller, and successively receives them again and delivers them to the siruper.

As all these machines and devices in the 20 line are in motion, and exercise their several functions upon a rapid-travelling continuous can-procession, it is of prime importance that their motions be accurately coordinated in point of time, in order to insure the continuity of the procession; also that the path of the cans shall be smooth, without danger of interruption or interference of any kind, thus avoiding jarring and wear and tear; and, finally, that the cans be initially supplied 25 in a crowd of relatively large numbers with the least labor, and thereafter automatically reduced to a procession file, and taken care of without the interference of any manual effort.

To secure these results is the object of 30 my present invention, and to this end I have combined in a unitary organized apparatus, the essential elements intimately related, of a feeder, drainer and siruper. For the feeder, in general, I may refer to the type shown in my Patent No. 1,512,652, dated October 21st, 1924. For the drainer, reference may be had to my Patent No. 1,397,153, dated November 15th, 1921. The 35 siruper may be seen in the type of my Patent No. 1,355,015 dated October 5th, 1920. I refer to these patents merely to supplement my present disclosure, if such be needed, and to enable me in the following description to 40 confine the explanation herein to such novel features and changes as are rendered necessary by the combination of these elements in reducing them to a unitary organization.

In the accompanying drawings, I illustrate 45 my combined machine in its preferred

form, it being understood that changes may be made without departing from the spirit of my invention as defined by the claims hereunto appended.

In the drawings, Fig. 1 is a top plan of 60 the machine.

Fig. 2 is a side view of the drainer.

Fig. 3 is a diagrammatic view, in plan, showing the general relation of the several components of the machine, and indicating 65 by the arrows the course of the cans.

Fig. 4 is an elevation of the gear-train for driving the timing screw.

Fig. 5 is a sectional detail of the second 70 table, the star-disks, and their driving gears.

Fig. 6 is a top plan of the hinged gate on the feeder.

Fig. 7 is an elevation of the same.

The combined or organized machine comprises, as shown in Fig. 1, the feeder A, the 75 drainer B, and the siruper C. These are herein illustrated in sufficient detail to satisfy the combination which constitutes my present invention, it being understood from the preliminary statement hereinabove of 80 the nature of the invention, that said general elements of the organized apparatus are more or less of standard and well known individual construction as is evidenced by my previous patents above mentioned. Consequently, such changes and departures from the prior art are those which are required by the combination, and these are herein 85 fully illustrated and will be particularly described. I may state that in order to 90 avoid complication, it must be assumed without particular illustration that the combined machine is carried by a suitable frame.

With regard to the feeder A, 1 is a horizontal table rotatable about its axis 2 and driven by an underlying gear 3 indicated in Fig. 1 by dotted lines. A supply platform 4 communicates with the table. From one side of said platform extends a fixed 95 guard flange 5, bordering the table rim throughout an arc thereof of slightly less than 180 degrees. Supported by the axis 2 about which the table 1 rotates is a bracket 6 which extends radially above the table and terminates short of the table rim. To the end of the bracket 6 is secured an arcuate 100 can-selecting arm 7 the outer face of which is concentric with and spaced from the guard flange 5, while the inner face is eccentric 105 to the axis 2. The platform 4 is supported by 110

centric to the outer face thus forming a tapering member, the free extremity of which is preferably provided with a small roller 8. The selecting arm 7 and the guard flange 5 thus form between them a passageway, the width of which is such that the cans 9 entering said passageway are reduced to single file.

From the other side of the platform 4 extends a fixed guard flange 10 which for a short distance follows the rim of the table 1 and then curves inwardly over said table and terminates under the bracket 6, in line with the inner face of the arm 7. The approach to the file-reducing passageway is guarded by a gate 11 carried by an arm 12 extending from the table axis 2, said gate having a spring hinge connection 13 with said arm as shown in Figs. 6 and 7, and 20 adapted to yield forwardly as shown by the dotted lines in Fig. 1.

In order to fully understand the feeder, it will be well, at this point, to describe its operation. The cans 9 are placed by the attendant upright upon the platform 4 and are slid therefrom to and upon the rotating table 1, in a crowd without any regard to order. The table 1 rotating in direction of the arrow carries the crowd of cans forward to the right; and said crowd, meeting with the forwardly yielding gate 11, pass it, and in so doing certain of the cans are pushed outwardly to the guard flange 5. As the front of the crowd meets the roller point of the selecting arm 7, it is divided, those cans on the outside being reduced to single file and thus enter the passageway, formed by said arm and the flange 5, while the other cans as indicated by the dotted-lines, pass to the inside of said arm 7 and are carried around along said arm and along the guard flange 10 to join the infeeding crowd, for another try to get into file.

With regard to the drainer B, suitable frame members 14 carry an annular vertically disposed housing 15 the inner surface of which forms a track for the cans to travel upon, said housing having an entrance on one side and an exit on the other side in its base. The travel of the cans is effected by a spider like propeller 16 within the housing, Fig. 2, the arms of which have members 17 with projecting pins 18 adapted to engage the cans between them and to carry them around within the housing and to drain them in the usual manner by reason of their inversion, certain perforated cap members 19, operated by a cam 20 being provided to confine their solid contents.

60 The communication between the feeder and the drainer is shown in Figs. 1 and 3. A segment of the surface of the table 1 underlies that portion of the drainer housing which includes the entrance thereto. The passageway in which the file of cans ap-

proaches the drainer, has for its outer wall at its terminus a timing screw 21, the threads of which engage each can, and regulate its advance, the rotation of the screw being timed to the rotation of the drainer propeller 16, so that each can is fed accurately to the engaging members 17 of the propeller. An arm 22 shown in dotted lines in Fig. 1, opposes the screw and serves to hold the cans thereto. As seen in Fig. 3, 75 the terminus of the passageway opens into the entrance in the base of the drainer housing in which there is fixed a directing cleat 23 set across the housing at an angle. Each can, in timely succession, due to the screw 21, is carried by the rotating table 1 up to said cleat 23 and is thereby swept from said table directly into the drainer housing. The exit for the cans from the drainer housing is, as seen in Fig. 3, on the opposite side 85 of said cleat 23, and the cans are swept therethrough by the rotation of the propeller.

With regard to the siruper C, I have herein shown a fragment, comprising its 90 shell 24, and its can holders 25. The communication between the drainer and the siruper as shown in Figs. 1 and 3, is more clearly seen in Fig. 3. 26 is a stationary second table in close relation to the exit 95 from the drainer housing, said table having a guard rim-flange 27 joining the cleat 23. The table is, at its other side in close relation to the can holders 25 of the siruper. 28 is a pair of star-disks, Fig. 5, mounted for 100 rotation above the second table 26. A rotatable turret 29 lies adjacent to the table 26, and a presser finger 30 extends from the table axis to and under the turret.

The cans issuing from the exit of the 105 drainer pass directly to and upon the table 26, and are engaged by the star disks 28 and carried around upon the table to a partial entrance into the holders 25 of the siruper. The rotation of said holders carries the cans 110 along the presser finger 30 until they are engaged by the turret 29 which registering timely with said holders trues them therein.

Power is led into the machine through the siruper. This is not herein shown, but it 115 will be sufficient to state that the transmission proceeds to the train of gears indicated in dotted lines in Fig. 1 to rotate the pair of star-disks 28 and the feeder table 1. Also by means of the bevel gears 31 in Fig. 5, the power is led from the star-disks 28, through the shaft 32, Fig. 1 to the gear train 33, Fig. 4, to rotate the timing screw 21. 34 in Fig. 1 indicates a can ejector for the siruper.

The complete operation of the combined 125 machine is as follows:—The unsealed cans, previously supplied with their washed solid product, are brought in trays to the platform 4, and by the attendant are placed upright upon the table 1 in a crowd, without 130

regard to order. The table rotating, carries the crowd forward past the gate 11 to the file selecting arm 7, the point of which forms the outermost cans into a file, the other cans being returned by said arm 7 and the flange 10 to join the infeeding crowd. The file of cans advancing meets with the guide 22 and the timing screw 21 and each can is swept off the table into the drainer housing 15 in front of the inclined cleat 23. Here, on account of the positive timing due to the screw 21 each can finds its engaging members 17 of the propeller 16 and is accurately taken up. By the rotation of the propeller, the cans are inverted above and drained of surplus moisture, and reverted below, so that when each arrives at the rear face of the inclined cleat 23 it is again upright and is swept out of the housing to and upon the second table 26. Thus there is one undrained can entering in front of the cleat 23 and one drained can being discharged back of the cleat, so that the propeller is kept full. From the table 26, the cans are swept off by the star-disks 28 and are guided by the presser finger 30 and by the registering turret 29 into the can-holders 25 of the sirupers 24. It will be noted that except for inversion in the drainer, the cans are swept along smooth level surfaces, without jar and with negligible wear and tear to the apparatus.

I claim:—

1. A combined feeder, drainer and siruper comprising a vertically disposed housing having in its base on one side an entrance and on the other side an exit; a series of can engaging members rotatable in a vertical

plane within the housing adapted to invert and revert the cans; a horizontally rotatable table, partially underlying a portion of the housing which includes the entrance of the latter; means associated with said table for automatically reducing a disorderly crowd of cans thereon to an orderly file; means associated with the table for directing the file of cans in timely succession into the housing entrance; a table in close relation to a portion of the housing which includes the exit of the latter; a siruper closely adjacent the last named table, having a rotating series of holders; and means for transferring the cans from said table in timely succession into the holders of the siruper.

2. A combined can feeder, drainer and siruper comprising a vertically disposed housing having in its base on one side an entrance and on the other side an exit; a series of can engaging members rotatable in a vertical plane within the housing adapted to invert and revert the cans; a horizontally rotatable table partially underlying a portion of the housing which includes the entrance of the latter; means associated with said table for directing the cans resting on its surface in timely successive relation into the housing entrance; a siruper; and a single rotating element adapted to transfer the cans directly from the housing exit to the siruper while preserving their timely relation.

In testimony whereof I have signed my name to this specification.

ALBERT R. THOMPSON.
